(57) **CLAIM**

I claim the ornamental design for a phallus retention device for seats, as shown and described.

DESCRIPTION

FIG. 1 is a perspective view of the phallus retention device for seats in a flat configuration;

FIG. 2 is a top plan view of the phallus retention device for seats of FIG. 1;

FIG. 3 is a bottom plan view of the phallus retention device for seats of FIG. 1;

FIG. 4 is a view in right side elevation of the phallus retention device for seats of FIG. 1 with the left side being a mirror image thereof;

FIG. 5 is a view in front elevation of the phallus retention device for seats of FIG. 1;

FIG. 6 is a view in rear elevation of the phallus retention device for seats of FIG. 1;

FIG. 7 is a bottom plan view of the phallus retention device for seats of FIG. 1 with the phallus retention panel separated from the base panel; and,

FIG. 8 is a perspective view of the phallus retention device for seats of FIG. 1 retaining a phallus and applied to a seat arrangement.

The broken lines shown in the drawings represent environmental subject matter that forms no part of the claimed design.

The cut lines shown on the strap portions of the design are meant to indicate an unspecified length of the article.
